UNITED STATES PATENT OFFICE

110,745

DESIGN FOR AN ILLUMINATED SHRINE

Leo Alter, Chicago, Ill., assignor to The Glolite Corporation, Chicago, Ill., a corporation of Illinois

Application March 31, 1938, Serial No. 76,201

Term of patent 14 years

To all whom it may concern:

Be it known that I, Leo Alter, a citizen of the United States, residing at Chicago, in the county of Cook and State of Illinois, have invented a new, original, and ornamental Design for an Illuminated Shrine, of which the following is a specification, reference being had to the accompanying drawings, forming a part thereof, and in which:

Figure 1 is a front elevational view of an illuminated shrine showing my new design;

Figure 2 is a vertical sectional view of the shrine of Figure 1, the view being taken substantially along the plane of the line 2—2 of Figure 1; and

Figure 3 is a longitudinal sectional view of the shrine of Figure 1, this view being taken substantially along the plane of the line 3—3 of Figure 1.

I claim:

The ornamental design for an illuminated shrine, as shown.

LEO ALTER.
